WATER HEATER CONTROL

Howard S. Miller, Jr., Altadena, and Michael J. Caparone, Arcadia, Calif., assignors to Robertshaw-Fulton Controls Company, Richmond, Va., a corporation of Delaware

Application May 5, 1959, Serial No. 55,783

Term of patent 14 years

(Cl. D52—1)

Fig. 1

Fig. 2

Fig. 3

Fig. 1 is a top plan view of a water heater control embodying our new design;

Fig. 2 is a front elevational view thereof; and

Fig. 3 is a side elevational view thereof.

The undisclosed side of the water heater control is substantially like the side shown except for the boss, and the rear is conventionally plain.

The dominant features of the design reside in the portions shown in full lines.

We claim:

The ornamental design for a water heater control, as shown and described.
